UNITED STATES PATENT OFFICE.

SAMUEL MATERSON MUSGRAVE, OF BELLS, TENNESSEE.

BRUSH OR BROOM.

SPECIFICATION forming part of Letters Patent No. 744,784, dated November 24, 1903.

Application filed April 30, 1902. Serial No. 105,364. (No model.)

To all whom it may concern:

Be it known that I, SAMUEL MATERSON MUSGRAVE, a citizen of the United States, residing at Bells, in the county of Crockett and State of Tennessee, have invented a new and useful Brush or Broom, of which the following is a specification.

The present invention relates to brushes and brooms; and the object thereof is to provide an improved structure in which soft flexible material may be employed for the body, said body being clamped close to the operative end, which will therefore be sufficiently stiff to properly perform its function, and being adjustably and detachably secured in order to provide for the wearing of the body and the replacement of the same by a new one when necessary or desirable.

The preferred construction is illustrated in the accompanying drawings, wherein—

Figure 1 is a perspective view of a broom constructed in accordance with the present invention. Fig. 2 is a longitudinal sectional view through the same. Fig. 3 is a cross-sectional view. Fig. 4 is a perspective view of the frame with the broom-body removed. Fig. 5 is a detail perspective view of the rear end of the broom-body.

Similar numerals of reference designate corresponding parts in all the figures of the drawings.

The invention is useful in all kinds of brushes and brooms for clothes, polishing, carpets, floors, and even whitewashing and painting; but in the present instance it is shown as an ordinary floor-broom.

In this embodiment a head-plate 10 is employed, to one edge of which is secured a handle 11 by means of a rivet 12 or other fastening. Projecting from the opposite edge of this head-plate are a pair of coacting jaw-frames, each of which comprises spaced side arms 13, which are secured by means of staples 14 to the side faces of the head-plate, their opposite ends being connected by a cross-bar 15. It will be observed that the side arms 13 are inwardly concaved, so that their intermediate portions are closer together than their extremities, as is clearly shown in Figs. 1 and 4. The broom-body 16 is arranged between these jaw-frames, being preferably made up of some pliable material, sea-grass

having proven an excellent as well as inexpensive substance that has good wearing qualities, while being very flexible. This material 55 is doubled upon itself and about a holding-bar 17, the ends of which project beyond the edges of the body and between the arms 13 of the jaw-frames. The holding-bar is fastened in place by means of a cord or cable 60 17^a, which is secured to the projected ends thereof and extends across the outer face of the doubled end of the body 16. The layers of the body are secured together by transverse lines of stitching, as 18, which are 65 spaced at desirable distances apart. The jaw-frames are clamped upon the broom-body by means of clips 19, that connect and are slidably mounted upon the lower ends of the side arms 13 and being movable upon the portions of said side arms that are disposed in divergent relation. Broom-head-engaging bars 20 are arranged longitudinally between the side arms 13, said bars being secured at their upper ends to the opposite sides of the 70 head-plate and having their lower ends attached to the cross-bars 15.

In practice the broom-bodies when new are slightly longer than the frames, so that when they are placed within the same, as shown in Fig. 1, the lower or operative end projects beyond said frame. The clamping-clips being pressed down toward the ends of the side arms, clamp the cross-bars securely upon the broom-body, while the longitudinal bars 20 85 prevent the bowing of the body laterally when the broom is being used. As a result the only portion of the broom which can "give" during the sweeping operation is the projecting end, the remainder of the body being 90 clamped. When this end becomes worn, it is only necessary to loosen the clamping-clips by sliding them upwardly toward the head-plate, whereupon the body may be moved downwardly a sufficient distance. Upon re-clamping the clips the cross-bars will be again clamped upon the broom, and at the same time, because of the convergent relation of the upper portions of the side arms due to their concaved construction, said arms will 95 clamp upon the holding-bar 17.

It will be apparent that this construction may be used in all sorts of brushes and brooms and that an extremely simple struc-

ture is provided in which soft pliable material may be employed in considerable lengths, this material being clamped contiguous to its operative ends so that it will not be too flexible. When the broom-body is entirely worn out, a new one may be substituted therefor, and the frame may thus be used over and over again.

From the foregoing it is thought that the

- 10 construction, operation, and many advantages of the herein-described invention will be apparent to those skilled in the art without further description, and it will be understood that various changes in the size, shape,
- 15 proportion, and minor details of construction may be resorted to without departing from the spirit or sacrificing any of the advantages of the invention.

Having thus described my invention, what

- 20 I claim as new, and desire to secure by Letters Patent, is—

1. In a broom or brush of the class described, the combination with a head of coacting jaw-frames connected with the head and having 25 side arms, a broom-body slidably located between the frames, a transverse holding-bar secured to the broom-body and having its ends slidably located between the side arms of the frame, and means for clamping the 30 frame upon the broom-body and the holding-bar.

2. In a broom or brush of the class described, the combination with a head, of coacting jaw-frames carried by the head and each having 35 inwardly-concaved side arms, a broom-body slidably located between the frames, a transverse holding-bar secured to the broom-body and having its ends slidably located between the concaved portions of the side arms, and 40 means connecting the corresponding arms of the frames and slidably mounted upon the concaved portions thereof for clamping the frame upon the broom-body and the holding-bar.

45 3. In a broom or brush of the class described, the combination with a head, of coacting jaw-frames carried by the head and each having inwardly-concaved side arms connected at their upper ends by a transverse clamping- 50 bar, a broom-body slidably located between

the frames, a transverse holding-bar secured to the broom-body and having its ends slidably located between the concaved portions of the arms, and clamping-loops slidably mounted upon the concaved portions of the 55 arms and arranged to move the jaw-frames toward each other and into clamping engagement with the broom-body and the holding-bar thereof.

4. In a broom or brush of the class described, 60 the combination with a head of coacting jaw-frames, connected with the head, a holding-bar slidably mounted between and engaged by the jaw-frames, and a broom-body also slid- 65 able between the jaw-frames and comprising pliable material doubled about the holding-bar and projecting beyond said frames.

5. In a broom or brush of the class described, 70 the combination with a head, of coacting jaw-frames, a holding-bar slidably mounted between and engaged by the jaw-frames, a broom-body also slid- 75 able between the jaw-frames and comprising pliable material doubled about the holding-bar, said bar having its ends projecting beyond the body, and a fastening device for the body secured to the projecting ends of the bar and extending across the outer face of said body.

6. In a broom or brush of the class described, 80 the combination with a head, of a handle secured to the head, jaw-frames comprising spaced side arms secured to the opposite side faces of the head and connected by cross-bars, said arms being inwardly concaved, a broom- 85 body slidably mounted between the jaw-frames, a cross-bar carried by the broom-body and engaging between the side arms, longitudinally-disposed body-engaging arms secured to the head and the cross-bars of the jaw-frame, and clamping-sleeves slidably mounted 90 upon the side arms of said frames and movable to clamp the same upon the bar and body.

In testimony that I claim the foregoing as my own I have hereto affixed my signature in the presence of two witnesses.

SAMUEL MATERSON MUSGRAVE.
